UNITED STATES PATENT OFFICE.

ARTHUR ROBERTS, OF EVANSTON, ILLINOIS.

REGENERATIVE COKE-OVEN.

1,313,208.

Specification of Letters Patent. Patented Aug. 12, 1919.

Application filed June 22, 1916, Serial No. 105,133. Renewed November 8, 1918. Serial No. 261,740.

To all whom it may concern:

Be it known that I, ARTHUR ROBERTS, a citizen of the United States, residing at Evanston, county of Cook, and State of Illinois, have invented certain new and useful improvements in Regenerative Coke-Ovens, of which the following is a specification.

The present invention has to do with improvements in regenerative coke ovens and the like. In the drawings I have illustrated the features of my invention as being embodied within a construction in which each oven of a bench is provided with its own individual regenerator or regenerators, as this is a very convenient method of applying the features of the invention. However, certain of the features of the invention are not necessarily limited to use in connection with constructions wherein there is provided an individual regenerator for each oven.

In previous constructions of regenerative coke ovens it has been found very difficult, if not impossible, to secure a uniform regenerating action. This difficulty has been experienced largely by reason of the fact that the gases or air passing through the regenerator tend to take a short cut through the same with the result that some portions of the checker structure are not worked up to their maximum regenerating capacity. One of the features of the present invention has to do with the provision of regenerator structures for coke ovens, whereby this difficulty may be eliminated. It has also been customary in the past to so relate the regenerator structures to the heating walls that a reversal of direction of flow in the regenerators has been accompanied by a similar or corresponding reversal of gas flow through the heating walls. The result has been that the said heating walls were not uniformly heated, and furthermore each portion of the wall was subject to rather severe strains occasioned by alternate expansion and contraction with the various reversals of flow. Another feature of my invention, therefore, has reference to an arrangement in which the heating gases always flow through the heating walls in the same direction and uninterruptedly, at all times notwithstanding the regular reversals taking place within the regenerators, thereby enabling me to secure a perfectly uniform heating of each and every portion of the walls. At the same time I thus eliminate

the severe strains of expansion and contraction previously referred to.

Another feature of the invention has reference to the provision of a construction such that the controlling valves will at all times be perfectly accessible to an operator outside of the bench of ovens. That is to say, this feature of the invention has to do with an arrangement of constructions including flues and the like, such that the control valves or dampers may be placed at the most convenient and accessible points with respect to the bench of ovens. Also in this connection another object is to so arrange and relate these valves that the desired reversals may be secured with a minimum number of moving parts, and with moving parts of very great simplicity.

Other objects and uses of the invention will appear from a detailed description of the same, which consists in the features of construction and combinations of parts hereinafter described and claimed.

Referring to the drawings:

Figure 1 shows a vertical cross-section through two adjacent carbonizing chambers with their heating walls and regenerators;

Fig. 2 shows a vertical longitudinal section taken on the line 2-2 of Fig. 1, looking in the direction of the arrows;

Fig. 3 shows a vertical longitudinal section taken on the line 3-3 of Fig. 1, looking in the direction of the arrows;

Fig. 4 shows an enlarged fragmentary vertical section through the control dampers and adjacent passages of one oven with its regenerators, being taken on the line 4-4 of Fig. 5, looking in the direction of the arrows;

Fig. 5 shows a horizontal fragmentary section corresponding to Fig. 4, being taken on the line 5-5 of Fig. 4, looking in the direction of the arrows;

Fig. 6 shows an enlarged end elevation of the control dampers shown in Figs. 4 and 5; and

Fig. 7 shows a plan view or horizontal section through the flues in the foundation.

Referring to Fig. 1 I have therein illustrated two adjacent carbonizing chambers 7 and 8. The chamber 7 has the heating walls 9 and 10, and the chamber 8 has the heating walls 11 and 12. The adjacent heating walls 10 and 11 of the consecutive carbonizing chambers 7 and 8 are close together, and as

a matter of convenience in illustration I have shown the recuperator wall 13 between them. This recuperator wall is shown in several figures as being of the type disclosed 5 in my co-pending applications for Letters Patent of the United States, Serial Nos. 875,503, filed December 4, 1914, and 69,995, filed January 3, 1916. However, I have illustrated the said recuperator walls between the heating walls largely as a matter of convenience, and I may say chiefly 10 for the purpose of supplying vertical air passages for carrying the air upwardly to the burners. It will presently appear that the said recuperator walls are not an essential 15 or even a necessary part of the features of the present invention.

As a matter of convenience in illustration also, I have shown each of the heating walls 20 as being built up from separate blocks which are recessed according to the principles disclosed and claimed in my Letters Patent of the United States, No. 1,132,685, issued March 23, 1915. However, in this case also 25 it will presently appear that any suitable form of heating wall may be adopted and that I have shown the type of heating wall which is herein illustrated simply as a matter of convenience. I will state, however, 30 that not all of the features of construction shown in the heating wall herein disclosed are found in the said Letters Patent, for the reason that the heating wall herein disclosed includes certain features not shown in the 35 said Letters Patent.

Bearing the foregoing facts in mind, each of the heating walls is illustrated as being built up from the notched blocks 14 to provide a mesh-work of gas passages, as is well 40 illustrated in Fig. 2. A row of burner passages 15 is provided above the upper portion of each heating wall, the burning gases from said burners striking against the baffle blocks 16 and then working their way downwardly 45 through the mesh-work of passages to a channel 17 which extends along beneath each heating wall. A sole passage 18 is formed underneath the sole of each oven, and the spent gases reach the said passage 18 from 50 the passages 17 by means of the down connections 19. At each end of the structure there is a down-comer 20 reaching downwardly from the end of the corresponding sole passage 18. The spent gases from each 55 sole passage travel downwardly, first through one down-comer and then through the other as the valves are reversed.

Reference to Fig. 1 will disclose a passage 21 above each of the recuperator walls 13. 60 It will also be seen from an examination of Figs. 1 and 3 that there are a plurality of burner connections 22 extending downwardly from the top of the bench to each of the passages 21. Examination of Fig. 3 65 will also disclose a plurality of vertical risers

23 leading from the upper portion of the recuperator wall into the corresponding passage 21. Reference to Fig. 1 will also disclose the burner connections 24 extending downwardly from each of the passages 21 to the upper portion of the corresponding heating wall, there being damper blocks 25 70 slidably mounted in the passage 21 for the control of the delivery of the mixture of air and gas through the passage 24 to the heating wall. When desired, there may also be provided damper blocks 26 for controlling the sizes of the openings 23 to thereby control the delivery of air into the passage 21. 75

The passages 23 lead upwardly from the recuperator wall and serve to deliver the air to the passage 21. It will be evident, however, that any other arrangement might be adopted as desired, and that as far as this feature of the invention is concerned the recuperator wall serves simply as a means 80 for providing passages for the delivery of air to the passage 21.

From the constructions thus disclosed, it will be apparent that the air flowing upwardly through the recuperator wall passes under control into the passage 21 where it meets the gas flowing downwardly from the connections 22. This gas may also be under control, inasmuch as it will ordinarily be delivered to the passages 22 from a header or the like. It will also be apparent that the mixture of air and gas passes downwardly through the connections 24 into the upper portion of the heating wall where it 95 burns.

In the particular construction illustrated each recuperator wall serves to supply air to two adjacent heating walls of two consecutive ovens, and a similar function is performed by each of the passages 21. It will be evident, however, that without departing from the spirit of my invention, each of these structures or passages might supply the air or mixture to only a single heating 100 wall, or to two heating walls of the same oven.

Each pair of heating walls and the intermediate recuperating wall is carried by a vertical wall or partition 27 which extends 115 upwardly from the foundation. It is thus evident that the load is transmitted directly to the foundation through these walls. Furthermore, the sole portion of each oven is carried by a series of transverse blocks 28 120 which extend between two of the walls 27. Consequently, the walls 27 carry not only the oven structures, but also the loads within the carbonizing chambers.

Between each pair of the walls 27 is a regenerator chamber or a pair of regenerator chambers, as is best shown in Figs. 1 and 2. In the construction illustrated a partition 28 runs longitudinally of the bench of ovens, so that underneath each carbonizing 130

chamber there are formed the two regenerator chambers 29 and 30. Underneath the central portion of the bench there are the longitudinally extending tunnels 31 and 32.

- 5 Reference to Fig. 7, which is a plan view of the tunnels 31 and 32, will disclose a common connection 33 extending between the end portions of the said tunnels. A connection 34 leads from the said common connection to the stack or to the draft producing mechanism, and dampers 35 and 36 are provided for connecting either the one or the other of the tunnels 31 and 32 to the said connection 34. Air connections 37 and 38 10 lead into the tunnels 31 and 32, so that air can be supplied to either of the said tunnels as desired.

By closing the damper 36, and opening the damper 35, the spent gases from the tunnel 31 will be delivered to the connection 34, and upon delivering air through the connection 38 the said air will reach the tunnel 32. By reversing the dampers 35 and 36, the spent gas from the tunnel 32 20 will be delivered to the connection 34, and by delivering fresh air through the connection 37, the said air will be delivered into the tunnel 31.

30 The inner end of each of the regenerator chambers 29 is permanently connected to the tunnel 31 by a down-connection 39 and in like manner the inner end of each of the chambers 30 is connected to the tunnel 32 by the down-connection 40. These connections are permanent and it is not necessary to use any valve mechanism at this point.

Underneath each of the recuperating walls is an air channel 41, and each end of each of the said air channels is connected to a 40 riser 42. The risers 42 alternate between the down-comers 20, as is very clearly illustrated in Fig. 5. These risers and down-comers may be conveniently built into wall structures 43 extending along underneath 45 the side portions of the bench.

The lower end of each down-comer 20 is carried forward by a connection 44, and the outer end of each of the said connections leads downwardly, under the control of a 50 valve 45, to a port 46. Underneath each of the connections 44 is a horizontal passage 47, the inner end of which is permanently connected to the corresponding regenerator chamber by a port 48, and the outer end of 55 which connects, under the control of a valve 49, with a port 50. The said port 50 connects to a passage 51, the inner end of which communicates by an offset portion 52 with the lower end of the next adjacent riser 42. 50 When operating on the air half of the cycle, the air flows from the regenerator through the port 48, connection 47, port 50 (the valve 45 being closed and the valve 49 being opened) through the connection 51 and connections 52 to the riser 42. Thence the air

is delivered upwardly to the air channel 41 and finds its way to the burners. On the heating half of the cycle the positions of the valves 45 and 49 are reversed, the valve 45 being opened and the valve 49 being 70 closed. Simultaneously the necessary reversals are made in the dampers 35 and 36 and in the air supply connections 37 and 38. Under these conditions the spent gas flows downwardly through the downcomer 75 20, across the connection 44 through the port 46, across the connection 47, through the port 48 into the regenerator chamber.

It will be understood that a set of connections and dampers such as are illustrated 80 in Figs. 4 and 5 is provided on each side of the bench of ovens for each oven, or for each pair of regenerator chambers. It will also be understood that the regenerator chambers 29 and 30 operate in pairs, one 85 of the said chambers working on air, while the other chamber is working on the spent gas.

It was previously stated that one of the objects of the invention is to provide an 90 arrangement whereby practically all portions of the regenerator chambers will be worked up to the maximum efficiency and regenerating capacity. For this purpose each of the said chambers may be provided 95 with a plurality of baffles 53, 54 and 55, between which are set the checker structures, 56, 57, 58 and 59. By this series of baffles the air and gas are caused to flow alternately up and down in passing between the 100 connections 48 and 39 or 40, so that it is quite impossible for the air or spent gas to shunt directly across the structure as will frequently happen when the said baffles are 105 not provided.

While in Fig. 2 I have illustrated the baffles as being composed of solid partitions, still it is evident that they might be formed in any other suitable manner, as for example by simply placing the bricks in some portions of the checker-work closer together than in the other portions.

While I have herein shown and described only a single construction embodying the features of my invention, still it will be 115 understood that I do not limit myself to the said construction except as I may do so in the claims, but that on the contrary I contemplate any equivalent constructions operating in equivalent manners to produce 120 equivalent results.

I claim:

1. The combination with a bench of coke ovens having heating walls and burners, of a regenerator chamber under each end of each oven, a pair of tunnels running lengthwise of the bench beneath the said regenerator chambers, a direct connection from each regenerator chamber to the adjacent tunnel, a down-comer from each end of each heat- 130

- ing wall; a riser adjacent to each down-comer, the upper end of each riser being in communication with the burners of the corresponding heating wall, a connection from 5 each regenerator chamber to a point adjacent to the corresponding riser and down-comer, and valve mechanism for connecting each connection to the adjacent riser or to the adjacent down-comer as desired.
- 10 2. In a bench of coke ovens having heating walls and burners in each heating wall, the combination with the said heating walls and burners of a regenerator chamber under each end of each coke oven, a common connection in communication with all of the regenerators on one side of the bench, a common connection in communication with all 15 of the regenerators on the other side of the bench, a down-comer from each end of the heating wall of each oven, a riser at each end of each oven leading to the corresponding burners, and means for placing each regenerator chamber in communication with the corresponding riser or down-comer as 20 desired.
- 15 3. In a bench of coke ovens having heating walls and burners, the combination with each oven of a regenerator chamber under each end of each oven, a down-comer from 25 each end of the heating walls of each oven, a riser at each end of each oven for each set of burners, and means for placing each regenerator chamber in communication with the corresponding down-comer or the corresponding riser as desired.
4. In a bench of coke ovens having heating walls and burners, the combination with each oven of a sole passage beneath the said oven and in communication with the 30 discharge sides of the corresponding heating walls, a regenerator chamber under each end of each sole passage, a down-comer from each end of each sole passage, an air connection for each set of burners, a riser communicating with each end of the said air 35 passage, and means for connecting each regenerator chamber with either the corresponding down-comer or riser as desired.
- 45 5. In a bench of coke ovens having heating walls and burners, the combination with the heating walls of each oven of a sole passage for the collection of spent gases from the said heating walls, a common connection for the delivery of air to each set 50 of burners, a regenerator chamber under each end of each sole passage, a down-comer from each end of each sole passage, a riser communicating with each end of each air connection, and means for placing each regenerator chamber in communication with either the corresponding down-comer or the corresponding riser as desired.
- 55 6. In a bench of coke ovens, the combination with a heating wall and burners therefor, of a sole passage for the collection of 60
- spent gases of the heating wall, a common connection for the delivery of air to the burners of the said heating wall, a regenerator chamber under each end of the said sole passage, a down-comer from each end of the sole passage, a riser to each end of the air connection, and means for placing each regenerator chamber in communication with either the corresponding down-comer or the corresponding riser as desired. 65
7. In a bench of coke ovens, a heating wall and burners therefor, a spent gas connection for the collection of spent gases from the heating wall, a common connection for the delivery of air to the said burners, a regenerator chamber adjacent to each end of the spent gas passage, a connection from each end of the spent gas passage, a connection from each end of the air connection, and means for placing each regenerator chamber in communication with either the corresponding spent gas connection or the corresponding air connection as desired. 75
8. The combination with a coke oven having heating walls and burners, of an air connection extending longitudinally of the oven and supplying air to the several burners, a riser at each end of the oven in communication with the said air connection, a sole passage beneath the heating walls 80 and receiving spent gas therefrom, a down-comer from each end of said sole passage, a pair of tunnels, a pair of regenerators, a permanent connection from the inner end of each regenerator to the adjacent tunnel, a connection from the other end of each regenerator, and valve mechanism for placing the last mentioned connections in communication with the corresponding down-comer or the corresponding riser as desired. 85
9. The combination with a coke oven having heating walls and burners, of an air connection extending longitudinally of the oven and supplying air to the several burners, a riser at each end of the oven in communication with the said air connection, a sole passage beneath the heating walls and receiving spent gas therefrom, a downcomer from each end of the sole passage, a regenerator beneath each end of the oven, and suitable valve mechanism for placing each regenerator in communication with either the corresponding downcomer or the corresponding riser as desired. 90
10. The combination with a coke oven having heating walls and burners, of an air connection extending longitudinally of the oven and supplying air to the several burners, a riser in communication with each end of the said air connection, a sole passage beneath the heating walls and receiving spent gas therefrom, a regenerator for each end of the oven, and suitable valve mechanism for placing each regenerator in connection with either the corresponding riser 105
- 110
- 115
- 120
- 125
- 130

or the corresponding end of the sole passage.

11. The combination with a coke oven having a heating wall and burners, of an air connection extending longitudinally of the oven and supplying air to the several burners, a riser in communication with each end of the said air connection, a sole passage receiving spent gas from the heating wall, a downcomer from each end of the sole passage, a regenerator for each end of the oven, and suitable valve mechanism for placing each regenerator in communication with either the corresponding riser or the corresponding downcomer.
12. The combination with a coke oven heating wall having heating passages, and burners at one end of said passages, there being a channel for the removal of spent gases from the other ends of all of the passages, of means for always supplying air to all of the burners in unison from either end of the heating wall, means for always removing spent gas in unison from all of the heating passages and from either end of the heating
- 5 connection extending longitudinally of the oven and supplying air to the several burners, a riser in communication with each end of the said air connection, a sole passage receiving spent gas from the heating wall, a downcomer from each end of the sole passage, a regenerator for each end of the oven, and suitable valve mechanism for placing each regenerator in communication with either the corresponding riser or the corresponding downcomer.
13. The combination with a coke oven heating wall having heating passages, and burners for delivering combustible mixture into one end of the passages, there being a channel for the removal of spent gas simultaneously from the other end of the passages, of connections at each end of the heating wall for supplying air simultaneously to all of the burners in common, and for removing spent gas from the channel, a regenerator for each end of the heating wall, and a set of valves at each end of the structure for connecting the corresponding regenerator to either the air supply connection or the spent gas connection.

ARTHUR ROBERTS.
